UNITED STATES PATENT OFFICE.

GEORGE E. GATES, OF EDGEWOOD, IOWA, ASSIGNOR OF ONE-THIRD TO JOSEPH W. FORWARD, OF EDGEWOOD, IOWA, AND ONE-THIRD TO WILLIAM H. STARK, OF YATES, MISSOURI.

COIN HOLDER FOR MAIL BOXES.

Application filed March 26, 1927. Serial No. 178,703.

This invention relates to coin holders for mail boxes, particularly rural free delivery mail boxes, and one object of the invention is to provide simple, reliable and efficient means for holding postage money and permitting the carrier to remove the same in a ready and expeditious manner.

A further object of the invention is to provide coin holding means which may be arranged within a mail box so as not to interfere with the free introduction or removal of mail matter and which may be manipulated by the carrier in cold weather without the necessity of his removing his mitten or glove, and also without liability of loss of the coins.

The invention consists of the features of construction, combination and arrangement of parts, hereinafter fully described and claimed, reference being had to the accompanying drawing, in which:—

Figure 1 is a side elevation of a mail box provided with my improved coin holder, the box being partly broken away to expose the holder.

Figure 2 is a vertical transverse section on line 2—2 of Figure 1.

Figure 3 is an enlarged longitudinal section on line 3—3 of Figure 2, showing the slide in coin holding position.

Figure 4 is a similar view showing the slide at the limit of its coin displacing or discharging position.

Figure 5 is a perspective view of the slide carrier block.

Figure 6 is a similar view of the slide.

Referring now more particularly to the drawings, 1 designates a mail box of any ordinary or preferred type, and which may be provided with an opening at one end for the insertion and removal of mail, said opening being shown in the present instance as closed by a hinged door 2 adapted to be secured in closed position by a suitable type of latch device 3.

Arranged within the box 1, so as to be accessible through the doorway, is the coin holder. This comprises a carrier block or support 4, which, as shown, is of oblong rectangular form and secured to the top of the box by bolts or other suitable fastenings 5. This block is provided at its sides with cut-away or recessed portions 6. Secured to the block by the bolts 5 is a wear plate 7 having side pieces or flanges 8 covering the oppo-

site sides of the block and terminating in guide edges 9 disposed opposite the recesses 6. The end of the block 4 which lies adjacent to and faces the doorway of the box 1 forms an abutment surface 10.

Mounted upon the block is a coin supporting and displacing or discharging slide 11. This is made of sheet metal and of channeled formation, comprising a bottom plate 12 bearing against the bottom of the wear plate 7 and side walls or flanges 13 projecting upwardly in parallel relation to and bearing against the sides 8 of the wear plate, said pieces or flanges 13 terminating at their upper edges in retaining and guide tongues 14 which engage the guide edges 9 of the wear plate and reciprocably support the slide in position on the carrier block. The bottom of the slide is preferably provided with a guide slot 15 engaging the headed end of one of the bolts 5, whereby the slide is additionally held in position, the end walls of the slot forming stops for engagement with the mentioned bolt, whereby the inward and outward sliding movements of the slide are limited. The portion of the slide in advance of the slot 15 forms a coin supporting shelf or platform 16. The channeled or trough-shaped slide thus formed is open at each end and provided at its rear end with a finger piece or loop 17 whereby it may be conveniently engaged and drawn outward into coin receiving position. At its opposite or forward end the slide is provided with an upturned flange 18 which may serve as an abutment against which the hand of the operator may bear in retracting the slide, and which normally serves as a detent to prevent slipping of the deposited coins 19 off the platform under any jars or vibrations which the box may be subjected to.

In the use of the device, when the owner of the box deposits a letter and desires to deposit a coin or coins for the pre-payment of postage, the slide 11 is drawn outward to the receiving position shown in Figure 3 and the coin or coins 19 deposited upon the shelf portion 16, as shown. The carrier on collecting the mail removes the coin or coins from the shelf 16, which is effected in a ready and convenient manner by pushing the slide back to the retracted position shown in Figure 4, causing the coin or coins by contact with the abutment surface 10 to be pushed forward and over the retaining flange 18. It will be

noted that the construction is such that the carrier may insert his hand through the doorway of the box with the palm facing upward and with a thumb or fingers engaging 5 the walls 13, and thereby conveniently push the slide backward, or he may, with his hand in such position, push rearwardly on the slide against the abutment flange 18. In either event, the palm of the hand of the mailman will be in position to receive the coins forced off the shelf, thus preventing any liability of the coins dropping out and falling 10 to the ground and becoming lost or displaced. This mode of operating the slide may be 15 readily and conveniently effected without the necessity of the mailman removing his glove or mitten from the hand employed for the purpose, as is required in the operation of some kinds of coin holding and dispensing 20 devices.

It will be evident that my invention provides a coin holding and dispensing device which is simple of construction, reliable and efficient in action, and capable of being applied to any ordinary type of mail box in a ready and convenient manner and without change of construction. The mode of operation described not only affords great convenience to the owner of the box in enabling him 25 to place the coins in position to be removed, but also reduces the time and labor of the postman in collecting the coins and prevents any possibility of the coins dropping out and becoming lost during abstraction.

30 While the preferred form of the invention is as shown herein, it will, of course, be understood that changes in the form, proportions and details of construction may be made within the scope of the appended claims, 35 without departing from the spirit or sacrificing any of the advantages of the invention.

Having thus fully described my invention, I claim:—

40 1. In a coin holder and dispenser, a horizontally disposed block adapted to be se-

cured to the lower face of a support and having its side edge portions formed with rabbets, guide members secured to the said side edge portions of the block and projecting 50 above said rabbets, and a coin supporting member slidably hung on the upwardly projecting portions of said guides.

2. In a coin holder and dispenser, a horizontal block having its side edge portions formed with longitudinal rabbets, a channel member secured to and embracing the lower portion of the block with its side walls extending above said rabbets, and a coin supporting channel member embracing the first 60 channel member having the upper edges of its side walls bent into embracing engagement with the upper edges of the first channel member whereby the coin supporting member is capable of slidable movement thereon.

3. In a coin holder and dispenser for a mail box, an elongated block adapted to be secured to the upper wall of the interior of the mail box, the longitudinal side portions of the block being formed with rabbets, a channeled member secured to the lower face of the block and having its side portions extending above the rabbets of the block to form guides, means for securing the block and channel member to said wall including 70 bolts one of which has a head disposed below the channeled member, and a second channeled member having embracing engagement with the first channeled member and having the upper edges of its side portions bent into embracing engagement with the upper edges of the side portions of the first channeled member above the rabbets, the second channeled member having a longitudinal slot receiving the said bolt head therein for limiting the sliding movement of said member, and a fingerpiece on the second member for accomplishing the sliding movement 75 thereof.

In testimony whereof I affix my signature.

GEORGE E. GATES.
